OCEANPLANE

James V. Martin, Garden City, N. Y.

Application April 10, 1937, Serial No. 136,190

14 Claims. (CL. 244—106)

This invention relates to aeroplanes and more particularly to the class of long range high speed planes adapted to fly over and alight upon the surface of large bodies of water. The primary object of the invention is to combine long range, high speed performance with the ability of the craft to ride out a gale of wind and waves on the ocean surface.

An aeroplane whether of the land type or of the type adapted to alight on the surface of the water has a higher center of gravity than merely surface or sub-surface craft, also an aircraft must, because of aerodynamic requirements, be spread out laterally more than surface craft and be built of lighter material, but the above noted characteristics make it more difficult for an aeroplane to withstand the buffeting of the waves and it is one of the objects of the present invention to adapt the aeroplane wings, bodies and floatation means to the form of the ocean wave motion with a view to mitigating the pounding and destructive force of the waves or "green water" of the waves on the ordinarily spreadout portions of the plane and at the same time to preserve the high lifting and low drag characteristics disclosed in my Patents Nos. 1,847,094, 1,973,007 and 2,068,300.

Objects in harmony with the primary object are as follows:

30 To provide means to superload the central wing surface for flight by juxtaposing auxiliary aerofoils and to alter the position of the said aerofoils in flight or while on the water so as to remove the said aerofoils from the region of green water when the oceanplane is floating.

To keep the wing ends out of the region of green water when the central body floats of the craft are in the trough of the sea.

To enable the ship's crew and passengers to safely pass from one body float interior to the other within a protected passageway within the central wing and to make said passageway adjacent to the engine rooms and to the wing retracting mechanisms.

45 To provide economy of material for strength by arranging the main frames of the floatation bodies to correspond with the fore and aft spars of the central wings and to locate retractable wing bracing between the same to resist wave impacts.

To provide novel means to load and discharge freight and passengers into and out of the wing and float compartments of an oceanplane.

To provide novel means of obtaining vision for 55 crew and passengers from within transparent bulg-

ing portions of the bodies or wings, so that drafts due to the plane's high speed can be prevented from interfering with vision beyond the opaque walls of the plane, and of streamlining some of such bulging portions and retracting others to 5 reduce wind resistance in flight.

To provide retractable wing bracing in flight combined with variable wing area.

To provide a form of motor cowling which improves the cooling of the power plants, affords a 10 better balancing arrangement for the oceanplane and reduces the propeller and propeller shaft housing interferences, as well as providing a simpler form of truss for the motors or propeller parts.

15 Figs. 17 and 30 are identical, in so far as the bulging streamlined glass is concerned with Figs. 1 and 2 of my copending application Serial No. 687,540, filed Aug. 30, 1933; now Patent No. 2,-081,437 and in so far as that subject-matter is 20 concerned the present application is a continuation in part of the former patent.

To provide a novel means of strengthening the wings of a plane for severe stresses of air or water and to enable the pilot to retract and house such 25 means without danger of collapse of the wings.

Other objects such as streamlining the retractable wing braces will become apparent as I proceed with the more detailed explanation of the invention as disclosed in the several drawings.

30 Fig. 1 shows my invention in the form of an oceanplane in side elevation and Fig. 2 is a plan view of the same while Fig. 3 shows the oceanplane in front elevation. Fig. 4 shows an enlarged view, partly in section of one of the two 35 boat bodies in the region of the wing and Fig. 5 shows an interior view taken looking toward the rear on the line 5—5 of Fig. 4. Fig. 6 shows a similar section of my oceanplane using an alternative wing such as that shown in Figs. 7, 40 8 and 9 or in Figs. 10 and 11.

Fig. 7 shows in side elevation my oceanplane with a superloaded wing of low aspect ratio, while Fig. 8 shows the same alternative type in 45 plan view and Fig. 9 shows the low aspect ratio oceanplane in front elevation and in rough water.

Fig. 10 shows still another alternative type of wing with upwardly bent wing ends to avoid the green water of the waves and superloading arrangements in plan view, while Fig. 11 shows the same in front elevation, and Fig. 39 shows in side elevation from a forward angle a view 50 looking outwardly toward one of the pilot's cabins.

15

30

55

Fig. 12a and Fig. 12b show in side elevation another alternative wing construction which could be employed on my oceanplane, but in this view which is broken into two parts the overlapping type of alternative wing construction is illustrated in connection with a double fuselage high speed plane. Fig. 13 shows in plan view the high speed plane and Fig. 14 shows the same with the overlapping wings extended and the wing braces in dotted lines, this view is in front elevation. Fig. 15 is an interior view showing sleeper accommodations aboard my oceanplane and Fig. 16 is also an internal view looking forward in one of the oceanplane bodies at the pilot's compartment.

Fig. 17 is identical in so far as the pilot's cabin and wing superloading disclosure is concerned with my copending application No. 687,540 now Patent No. 2,081,437, in relation to the pilot's means of vision on the sides and backward. Fig. 18 is a view in section taken looking forward on the line 18-18 of Fig. 12. Fig. 19 is an enlarged front elevation view of my speed plane showing the wing bracing in relation to the port body and the telescopic wing on one side. Fig. 20 is an enlarged view partly in section taken transversely on a plane cutting the body of Fig. 19 where the main wing braces are attached and Fig. 21 is a fragmentary view in side elevation of the said body showing the slot for travel of the wing brace up into a recess in the lower side of the wing which is indicated partly in section at the top of the figure.

Fig. 22 is a view showing how one of the wing braces is attached to a wing spar and Fig. 23 is a rear elevation, partly in section showing the internal wing support for the said brace and operating means therefor. Fig. 24 shows in front elevation how one of the telescopic wing's struts unites with a brace of the main wing, while Fig. 25 shows the upper end of the said main wing brace and Fig. 26 is a view partly in section taken on the line 26-26 looking down along the parts shown in Fig. 24.

Fig. 27 shows a typical wing brace with adjustable streamlining and this view shows in section how the walls are arranged; Fig. 28 is a view of an alternative wing brace with an inflatable means of adjusting the streamlining, while Fig. 29 illustrates what a sectional end view of such braces looks like when the streamlining is collapsed on one side of the said brace.

Fig. 30 is a view looking down on the transparent bulges which adjoin the cabin shown in Fig. 17 and insofar as the bulges and pilot's cabin are concerned with this view is identical with a portion of Fig. 2 of my copending application No. 687,540 now Patent No. 2,081,437, heretofore referred to. Fig. 31 shows a typical passenger observation seat in a body or wing of my oceanplane. Fig. 32 shows, partly in section, a view looking down along one of the side walls of a typical passenger body and my novel device to allow vision outwardly, up and down and forwardly and rearwardly while avoiding both wind resistance and drafts. Fig. 33 is a view looking at the said wall from the inside. Fig. 34 shows an alternative arrangement for vision through the side wall of my oceanplane body, while Fig. 35 shows the same device as used by a passenger outlined in dotted lines. Fig. 36 shows an enlarged view of the mechanism by which I move my vision panel into place and Fig. 37 views same from the outside of the body wall, while Fig. 38 is a view, partly in

section taken on the line 38-38 of Fig. 36. Fig. 39 was described following Figs. 10 and 11 above.

Fig. 40 is an enlarged view in side elevation showing how I remove the Wragg type flap from proximity to the waves. Fig. 41 is a fragmentary view of the said means looking downward along one of the fuselage walls which is shown in section and Fig. 42 shows operating means to move the said Wragg flap. Fig. 43 is a view partly in section taken along the lines 43-43 of Fig. 17, showing how the pilot may look backwardly beyond the side wall of his cabin.

Fig. 44 is a view looking down into a portion of the starboard body of my oceanplane where the Wragg compounding device crosses the body walls which are indicated in section. Fig. 45 is a similar view of the port body and Fig. 46 is a view, partly in section, looking from the rear in elevation of Fig. 45. Fig. 47 is an enlarged view of the mechanism for attaching or detaching sections of the Wragg type wing and Fig. 48 is a view, partly in section, taken along the line 48-48 of Fig. 46.

Fig. 49 is a fragmentary view inside the cowl 9a shown in Fig. 12a as inclosing a radial motor, the upper wall of the cowl is shown in section in Fig. 49 and Fig. 50 is a view of the said cowl, partly in section, taken on the line 50-50 of Fig. 49.

Fig. 51 shows a typical side view of my traveling belt to move my internally telescoping wings and Fig. 52 is a cross-section view of same taken on the line 52-52 of Fig. 51.

Fig. 53 shows, partly in section, the internal wall connection of the retractable brace 110 with central wing 1c of Fig. 19.

Like numerals refer to similar parts throughout the several views and I shall proceed with a more detailed description of my inventions: 1 designates the main wing of my oceanplane, which in Figs. 1, 2 and 3 is shown as continuous, excepting for small portions of the lower surface and still 40 smaller portions of the upper surface, over the two boatlike bodies 2; smaller wings 3 telescope through the lateral ends of the main wing 1 and are each equipped with trailing edge ailerons 4. Fore and aft wing spars 5 and 6 respectively are 45 located, one forwardly and one rearwardly of the said smaller wings 3 and wing trussing after the fashion shown in my former patents above referred to and in my co-pending Serial Nos. 687,540 now Patent No. 2,081,437 and to #674,566 filed June 6th, 1933 now Patent No. 2,081,436 afford tracks and other guides for the said wings 3, and operating means for the said ailerons 4, from either one or both pilot cabin location 7; air-cooled motors 8 are located within low drag cowlings 9 and attached to the main wing trussing or alternately to the fuselage fire wall 9e of Fig. 12a and these motors drive suitable propellers 10. A partition wall is located on the forward side of the spar 5 and a passageway 11, large enough for human occupation, extends through the forward part of the wing and enables a man to pass from one of the boat bodies 2 to another and also affords access to the different engine compartments within the cowlings 9. An auxiliary aerofoil 12 known as a Wragg compound is located adjacently to rearward and slightly below the trailing edge of the main wing and held in that position by a torque tube support 13 journaled in bearing housings 13a in the walls 2a of the bodies 2 and also in bearings in the wing brackets 14 (see Figs. 40 and 41). This Wragg wing 12 is operable from within the bodies after the manner disclosed in my copending Serial No. 687,540 now Patent No. 2,081,437 for the purpose of altering the lift and 75

drag characteristics of the main and auxiliary wing combinations and in addition I provide a slot 15 in both the walls of the bodies 2 and in the wing brackets 14 and means to shift the location of the said Wragg and its journalled supports and their bearings to a position indicated in dotted lines in Fig. 1 and in Fig. 40, above the trailing edge of the main wing and away from the crests of the waves to protect it from contact with green 10 water.

10 A rear stabilizer fixed control 16 is located on top of the rear of each said boat body at its extreme rear and high up so that it remains clear of the water indicated by the broken line X—X of Fig. 1. A movable rear flap 17 is attached to 16 and vertical rudders 18 are located on the rear ends of both said bodies 2.

Light and vision is afforded through port holes 19 in the bodies and wings of my oceanplane and 20 also through special windows 20 and a rounded and bulging type of window 21. The boat bodies 2 are internally strengthened by decks 22 and bulkhead frames 5a and 6a and by numerous smaller transverse frames 23. The wing skins 24 are of the double sheet metal type shown at 24 of Fig. 6 and Fig. 21 or of the alternate forms disclosed in my former patents and copending serials above referred to 24' indicates fillets between lower wing surfaces and the hull side walls.

30 The smaller telescopic wings 3 are guided between rollers 25 on the spars 5 and 6 and also between tracks 26, see Fig. 4, which are provided with belts 27 and these belts have a tough rubber of soft rather than hard rubber consistency in 35 contact with the smaller wing and this soft rubber 28 has a bond to a stronger and less flexible material 29 which in turn is bonded to V metal pieces 30 which serve as actuating means to prevent slipping of the belt when it is driven by rollers after 40 the fashion indicated at 9e of Fig. 11 in my copending Serial No. 674,566. With this arrangement and the smaller wings attached to the belts which compress them tightly between the tracks 26 it will be seen that there will be no friction between the tracks and the wings 3 while the belts 45 themselves can be provided with anti-friction rollers or an essentially slippery track surface, for further belt arrangements see Figs. 6 and 7 and 15 of my copending serial above mentioned. Attention is called to the built-up nature of the wing 50 skins employed, either that indicated at 24 in Fig. 6 of the present disclosure being understood as used on all the wing surfaces or else the various alternative double wing skin stressed skin constructions previously disclosed in my patents 55 above referred to or in my Serial No. 674,566, see Figs. 16 and 17; also the built up nature of the spars 5 and 6 and of the spars 31 of the smaller wings 3, and of the frames 5a and 6a as well as 60 frames 23 and also of the boat bottom construction 32 all of which require great lightness combined with strength and short interval reinforcement. The double skin 24 may profitably be employed in conjunction with the structure 32 and 65 in Fig. 4 fuel ballast tanks 33 are located between the outer boat bottom and the lower deck surface of the interior hull so as to provide additional protection against water entering the said hulls and also to afford a ready method of trimming the 70 craft by means of pipe leads 34 with regulatable valves 35 which lead upwardly through frame 5a to one of the control rooms of the oceanplane. Such control room may readily be located in connection with an engine room 41 (see Figs. 7 and 8), 75 located forward of the forward wing spar 5 and

containing the motor 48 or to one located forward of the passage 11 as heretofore indicated.

Stairs 36 and an elevator 37 facilitate the up and down movement of both passengers and goods from one deck to another and also as shown in Fig. 6 from an external lighter or tender 38, which is prevented from injuring the hull by guard strips 39 which run along the lower hull in a horizontal direction so as not to create drag. The type of elevator which I have devised for use on the oceanplane can be used not only to raise and lower passengers and goods from an external platform into the wings and hulls but can convey same while the plane is in flight from the lower decks of one of the boat hulls through the wing 1 to any desired deck of the other hull. This is accomplished by providing a track 39a on which is mounted a traveling crane 40 driven by its own electric motor 41 along the track 39a subtending from the under side of the wing upper skin 24. Special double 20 wall hatches 42 are closed water tight by covers 42a with inclined rubber covered edges 42b and these hatches are located in a thwartship line in the passageway 11 and directly under the track 39a and the traveling motor hoist 40. I also provide a means 36 of passing from within the wing through an opening 42c in the upper wing skin. Freight compartments 43 are provided not only between the decks 22 and bulkhead frames 23 of the hulls, but also in the wing spaces 46 not otherwise occupied. Entirely inclosed motors 48 are located within the said engine or control rooms 41, in this connection see Figs. 7, 8 and 9 which disclose an alternative form of superloaded wing 1a of sufficiently short span to keep the wing ends 35 out of the green water. It is also contemplated to retract the Wragg compounding flap 12 after the manner shown in Figs. 1, 40, 41 and 42 and Figs. 44 to 48 inclusive. The details of this I shall 40 now describe. As previously pointed out I provide a slot 15 in both the walls of the bodies 2 and also in the bracket 14 which is rigid with the rear spar 6 and holds the Wragg wing 12 in spaced apart relation to the wing. A suitable antifriction bearing is located in bearing housings 13a, see 45 Figs. 41 and 42, and I also provide similar bearings for tube 13 in the wing bracket 14. To lower the drag for full flight the pilot, by means disclosed in my copending serial No. 687,540 now Patent 50 No. 2,081,347, Figs. 7, 8 and 9, operates the torque tube 13 so that all the three sections of the Wragg are held in the full line positions shown in Figs. 1 and 40. In this operable position the bearing 55 housings 13a are at the rearmost and lower portion of the slots 15. The outermost Wraggs are secured to the torque tubes 13s on the starboard side and 13p on the port side and 13p for example can end at a differential bevel gearing 49 similar to that shown in Figs. 7, 8, and 9 of my Serial 60 No. 687,540 now Patent No. 2,081,347, but with important differences which I shall point out as we proceed. In the present case I employ three instead of two Wraggs and I provide means not only for the joint and differential operation 65 of the outermost Wraggs, but also means by which the pilot may operate the central Wragg 12c either in conjunction with the other Wraggs or it may be operated independently by itself. To accomplish this rather complicated manoeuver 70 75

I supply a larger torque tube 13c as the main support for the entire Wragg system of auxiliary wings. To this 13c is rigidly attached the 12c Wragg and by means of suitable bearings 50 where ever needed the smaller tubes 13s and 13p are carried: It is immaterial which of the two fuselages be employed to contain the differential gears 49, but for illustration I use the port body 2 and with that in mind I provide slider bearing blocks 13a located in the body slots 15 of both walls of both bodies: The large tube 13c extends from its bearing in the port side slider block of the port body 2 and continues across the said port body to the starboard wall thereof where it is again carried by a slider block 13a: Thence the large tube 13c spans the gap between the two fuselages or bodies 2 and enters a slider block 13a in the port side of the starboard body. In planes like that illustrated in Figs. 7, 8 and 9 it is desirable to use the port and starboard Wraggs as ailerons and to use the center Wragg only for landing or climbing also it should be used in conjunction with the said port and starboard flaps for alighting and quick get-a-way. To accomplish this I arrange the differential gears 49 in the center of the port fuselage: These gears intervene between the smaller tubes 13s and 13p and are shown located between the ball bearings 50 Figs. 45 and 46, the larger tube 13c forming a housing and support for bearings 50 and tubes 13 and differential gears 49. Suitable slots 51 are cut in the larger tube to permit the limited movement desired in the smaller tubes as distinct from the larger tube 13c. For greater compactness I have shown the journal 52 for the differential as located between the smaller tubes 13s and 13p and located on an extension of 13p instead of the yoke I showed in my former application above identified. An operating lever 53 is connected with the pilot's cabin by suitable control wires 54 and bracket arms 55 hold the control wire pulley in desired position so that when the pilot desires to move the two smaller Wraggs 12p and 12s in unison in the same direction he moves the lever 53 in a fore and aft direction by wires 54, but when he desires to create a differential action he moves the lever 53 from side to side by wires 56 which lead to pulleys carried by the slider bearing blocks 13a and thence to the pilot's cabin. It should be noted that the brackets 55 are mounted on the slider blocks 13a so that the entire system may be moved forward in the slots 15 to free the Wraggs from encroachment of green water when the oceanplane is riding out a gale of wind and water on the ocean surface. To accomplish this I provide a rack 57 such as that disclosed in my co-pending Serial No. 674,566 now Patent No. 2,081,346 (see Figs. 30 and 34) and I also provide a pinion gear 58 after the form shown in Figs. 29, and 31 of above patent, but in the present case I have the rack secured to the side wall 2a of the port fuselage 2 adjacent the slot 15 and an electric motor 59 to move the slider block attached both to the pinion 58 and the slider block 13a so that the slider block is forced by either the said motor and pinion 58 or by alternative hand crank 60 to travel along the slot 15, by a smaller shaft 61 and two sets of gears 61a and 61b I am able to communicate the pinion movement to another such pinion on the slider block 13a on the port side of the starboard body and thus create a like impulse for the large tube 13c to move forward and upward in its slider block in

the starboard body: the small tube 61 is located neatly between the outer tube wall 13c and the inner tube 13c.

Since it is necessary to operate the Wragg central flap under different conditions from the two outer Wraggs 12p and 12s I have located a bracket 62 on the fore part of the large tube 13c in the fuselage 2, port body, and on the port side of the differential 49; this bracket supports a journalled control 63 in the form of a yoke operated by a push and pull rod 64 from the pilot's position or in lieu thereof a spring 65 may be employed to keep the said yoke 63 in one position while the member 64 may be a tension wire leading to the pilot's cabin. A slot 66 in the top 15 and another in the bottom of the large tube 13c permits the ends of the yoke 63 to enter into locking engagement with gear type teeth 67 located on the internal tube 13p so that when thus engaged the pilot can operate all the three Wragg 20 flaps together in the same direction by moving the lever 53, but if he desires to disconnect the large tube 13c from the rotational movement of the smaller tubes he will move lever 63 and this will pull its ends along the slots 66 till they are clear of the internal tube teeth 67: Then he may operate the two end Wraggs independently of the center Wragg and I provide a simple wire control 68 to enable the pilot to control the center Wragg 12c when the same is disconnected. The slight angles which the Wragg will take relative to the inner tubes will not seriously affect the operation of the disengaging means 63 and it will be understood that only when the slider blocks 13a are at their lowest and most rearward position will it be desired to operate any of the Wraggs about their axes for oceanplane control and then all the control cables will be taut. A flaring guide 69 such as I disclosed in Figs. 26 and 27 of my copending application Serial No. 674,566 now Patent No. 2,081,346 may be employed to guide the Wragg flaps in their course to a safe-from-the-water position above the rear trailing edge of the main wing of the oceanplanes. In so far as the disclosures of my formerly filed copending application No. 687,540, now Patent No. 2,081,347 relates to the subject matter of the differential action of the Wragg type wings for lateral control this present application may be regarded as a continuation in part of the former patent as divisional subject matter therefrom.

I shall now describe my invention also disclosed in the aforesaid application relating to outwardly bulging vision means for aircraft, but in the instant case I have improved my former disclosures as seen in Fig. 1 of the above application which is Fig. 17 of this application and Fig. 2 parts of which are Fig. 30 of this application. Reference is hereby made to my co-pending Serial No. 189,220, filed Feb. 7, 1938, for claims running to my vision bulb invention. At the high speeds becoming prevalent in modern planes the air velocity interferes with vision when a pilot or observer puts his head beyond the external walls of an inclosed body or wing. It is old in the art to provide glass or plastic glass substitutes in line with the side walls of the plane to close openings so that vision can be had therethrough, but I go further and bulge outwardly the plastic transparent substances so that an observer can look outwardly and by putting his eyes beyond the line of the aeroplane body side wall he can see upwardly or downwardly or fore and aft and at the same time his eyes will not feel the severity of the high wing 75

drafts and also I go still further and by carefully streamlining the external bulges I save the air turbulence which would result if the openings were not thus streamlined. In the figures above referred to and in Figs. 12, 18, 32 and 33 I show a plastic material bulge 70 which in Figs. 17, 30 and 43 extends backwardly outside of the closed wall 2a of the fuselage or airplane body. In Fig. 43, 71 represents the forward end of the rearward wall 2a near the back 72 of the pilot's seat. In Figs. 12 and 18 I show the bulge 70 located both above the observer's position and also on both sides thereof. But, since it may not be necessary on long trips to have the bulges located outwardly of the streamline surfaces of the plane thus creating drag and increasing the gasoline consumption.

I have invented and in Figs. 32 and 33 disclosed an easily removable bulging panel 73 with a handy hand clamp 74 to secure it in place after its opposite end has been located behind convenient corner brackets 75. I also show how a straight panel of glass 76 can be located in the wall below the opening and moved readily into place by an automobile type window raiser 77. In Figs. 34 to 38, inclusive, I disclose a still more improved type of vision bulge device for use on passenger liners or military planes: Here is shown a rounded bulge 78 which fits neatly into a hole in the side wall 2a of the plane and enables a person standing as indicated by dotted figure in Fig. 35 to look in several directions. The bulge 78 is mounted on a frame 79 which is carried by a lug 80 rigid therewith and this lug has an expanded part 81 which is guided for movement in a slot 82. This slot 35 has edges 83 which confine the expanded part 81 within the slot path and a flexible cable 84 is operated by a hand crank 85 to retract or extend the said bulge 78 when ever desired: For example when the bulge 78 is not needed a straight glass 40 76 located within the double wall 2a of the aeroplane body is in place to close the opening in the body side wall and the transparent bulge 78 is located out of the way of passengers as shown in Fig. 34, but when a passenger desires to look 45 downwardly at some terrestrial objects he manipulates the crank 85 and this crank operates the usual form of automobile window raiser at the same time it pulls the cable 84 around the guide pulleys 90 to lower the bulge 78 until its holding 50 lug 80 and 81 is drawn into the position shown in Figs. 36 and 38. At this corner to provide for an easy turn in direction I have provided an additional guide roller 91 and an indenture 92 in the lug 81; also I have certain right angle slots 55 93 in the lug itself so as to let the cable 84 lead in the best directions to pull the lug in desired directions: After rounding the corner as shown the lug will bring the bulge 78 into the position shown by Fig. 35.

60 As vision is becoming a most important concern for all types of aircraft I have devised special transparent panels 94, see Figs. 12, 31, 16, 8 (see also 21 in Fig. 1), and in the wings of Fig. 9 where the transparent panels are arranged conveniently for vision downwardly through the side walls of the aeroplane body or wing. Note in Fig. 31 the convenient location of passenger observation chairs 95, seen also above 21 in ascending tiers in the rear fuselage portion 70 of Fig. 1 and the location of such a panel for downward vision of the pilot in Fig. 12 as well as the panel 94 for use of the oceanplane captain from his navigation room shown in Fig. 16.

As still another alternative to escape the green 75 water impact upon the wing ends of an oceanplane

I show in Figs. 10 and 11 the wing ends bent upwardly to escape the more severe wave crest portions. In Fig. 11 I have indicated the green water as X and the spray or whitecaps as Z and also in Fig. 9 I have indicated how the wave movement 5 will act about the bodies and wings of my oceanplane without doing damage although the broken crests of the waves and spray go completely over the wings and bodies as will occur in gales and storms.

10 As still another form of wing which can be employed on my oceanplane to escape the disastrous force of the green water I show in Figs. 12, 13 and 14 an overlapping type of wing which has particular significance both for planes desiring to escape the action of green water on their wing ends and also for very high speed double bodied planes such as disclosed in the high speed pursuit bomber illustrated in Figs. 12, 13 and 14 of the drawings.

20 In order to obtain very high speeds it is necessary not only to retract a large portion of the landing wing area, but to keep the wing into which the smaller wings are retracted of as little thickness as possible to reduce its drag influence. In 25 Fig. 12 is shown the profile of a wing 1c, which is much thinner than my prior disclosures (see also copending applications above noted) of overlapping telescopic wings and a type of wing which therefore has an extra need for retractable wing 30 bracing.

To meet the new demand for strengthening the wing I have disclosed in Figs. 12, 13 and 14 smaller wings 1d and 1e telescoped respectively one with 35 in the port lateral end of the main wing 1c and the other 1e and lower small wing through the starboard side of the said main wing 1c.

These wings are guided on tracks 26 with belts 27 to prevent friction between the said tracks and the retractable wings and each said smaller wing is provided with a wing spar 31 in line with one of the tracks 26 so that when the wings are retracted into overlapping relationship like that shown in Figs. 9 and 11 of Serial No. 674,566 and Figs. 1, 2 and 3 of Serial No. 687,540, both copending, and in Figs. 12, 13 and 14 herein they will unite with each other and the internal wing bracing of the larger wing 1c to strengthen that wing for the full flight stress condition. I also show the front spar 5 and the rear spar 6 in Fig. 12 and cantilever intermediate spars 5a and 6a located between the said smaller wing spars 31 and also stub spars 26 to carry the spar stresses to the double wing skin 24: I also show rear wing flaps and ailerons 12p, 12c and 12s corresponding 50 in function to the Wragg flap disclosures surrounding Figs. 7, 8 and 9, also 40, 41 and 42 as well as 1, 2, and 10 and 11. Naturally the feature of retracting these flaps in Figs. 12 and 13 to an elevated position behind the main wing will not 55 apply to the sort of flaps shown in the Wragg type drawings and the Wragg type can be substituted for the type shown in Figs. 12 and 13 and if so substituted would still further lower the drag of the main wing 1c.

60 The particular novelty which attaches to the type of overlapping wings shown in Figs. 12, 13 and 14 lies in the novel way I brace them progressively for varying conditions of stress, for example to either alight or get away from the ground 70 the wings 1d and 1e will be fully extended, but with a heavy load of gasoline and bombs 96, see Fig. 14, these wings may be too weak with their internal bracing alone so I supply the external bracing shown in dotted lines. After the plane 75

is in the air and not brought up to its high speed, but kept at a safe flying speed I progressively retract both the outer wings and their bracing and lastly the bracing of the main wing between the 5 two fuselages. The first step in this process is accomplished by the pilot operating the retracting motor and mechanism for the wings as disclosed in my copending application Serial No. 674,566. The outer wings are externally braced by a 10 tension and compression diagonal 97 journaled to tubular support 31a affixed to the spar 31 (forward spar) by a bracket 31b and the lower end of 97 is rigid with another brace 98 also journaled about the tube 31a, see Fig. 22. These journaled 15 braces form with the tube 31a a triangular brace or truss for the said smaller wing with the outer end of 97 supporting the small wing at approximately the center 99 thereof, see Fig. 19, of its extended portion when fully extended. Small 20 ball bearings 100 permit easy movement of the wing 1d along the tube 31a until the end of 1d reaches the position indicated at 99 of Fig. 19; then the electric motor 101 is started by contact of gear teeth 102 with gears 103 in the top of 25 brace 98 or by contacts made by the pilot through electric push buttons and through reduction gear housed in 104, see Fig. 23, the brace or strut 98 is folded backward into slot 105, the angle cut away in Fig. 22 between the bracket 31b and the 30 gears 103 being made sufficient for a substantially right angle movement of 98 into the wing slot so that when it is finally housed it closes the slot substantially flat with the lower wing surface after the fashion shown in Figs. 28 and 29: As the 35 brace 98 retracts it carries with it the diagonal 97 which retracts into slots in the wing as revealed in Figs. 28 and 29. The lower end of brace 98, see Figs. 24 and 26, has been wedged in the movable arm 106 so as to transmit stresses 40 in the directions indicated by the arrows 107. At this time the inner part of the wing 1d will have gone from position 108, see Fig. 14 to position 109 just beyond the main wing 1c center and its corresponding small wing 1e on the starboard side acting similarly will have retracted into a slightly overlapping position with its mate 45 1d. An automatic stopping arrangement such as I have shown in my copending Serial No. 674,566 and in my Patent No. 1,672,985, or an electric cut-out of conventional pattern is contemplated so that when the wings 1d and 1e reach the stations such as indicated at 109 for 1d the wing 50 retracting shall be delayed until the braces 97 and 98 are fully retracted and housed after which 55 the complete retraction may proceed until the end of the small wings are neatly housed within the ends of the large wing and form with said ends flush end closures. When the telescopic wings are half retracted either the aeroplane 60 motors may be opened up so that higher speed is attained or the pilot may keep to comparatively low speeds and retract the external braces 97 and 98 as described. Then he may proceed by pressing another electric button to retract and 65 house the brace 110 which carries the arm 106 and is rigid with braces 111 and 112; this brace is retracted by a small electric motor with proper wing contacting connections and wires as disclosed in my lighting wires shown in Fig. 11 of my 70 copending Serial No. 674,566 and operates like the brace 98 but without so much complication as there is no lateral movement about a tube such as 31a of Fig. 22, but only a simple journal and appropriately placed wing slots in the lower 75 surface of 1c to accomodate the braces 110, 111

and 112. As the brace moves upwardly around its journal 113, see Fig. 25, a rod 114 located within the said brace 110 and journaled at its top to the end wall of the main wing 1c at 115 is forced downwardly and along the slot 116 relative the 5 lower end of 110 so as to push on arm 106 at journal 117, see Fig. 24, and thus move the said arm about journal 118 into the dotted line position indicated in Fig. 24. The attached braces 111 and 112 are understood to be housed as shown 10 in Figs. 28 and 29 when finally retracted, but diagonal 112 forms a connection inside the fuselage wall, see Figs. 20 and 21, with another brace 119 and at their union is found a roller 120 for movement in a slot 121 with flanges such as 83 of Fig. 15 36, so arranged that when in the extremely extended position they form a continuous transverse-to-flight trussing connection through a specially strong fuselage trussing member 123 to a similar bracing truss 124 and 125 with its corresponding brace 126 like 119. In applying my novel wing bracing care must be taken to adapt it to the conditions; for example, if an oceanplane 20 wing without telescoping wings is employed the only braces needed would be those corresponding 25 to 112, 125 and/or 126 of Fig. 19 and these should be located at or near the frames 5a and 6a (Figs. 5 and 6) which correspond in function with frame 123 of Fig. 20. Such braces will add great strength 30 to the connections between the hulls and the main 35 wing to resist wave action, and, for flight, can be retracted and housed as indicated. Naturally the brace in any one of these trusses which is most conveniently located can be selected for the small electric motor operation, thus brace 119 35 can be motivated instead of brace 110 for the truss consisting of 110, 111, 112 and 119. Similarly the truss which extends between the two fuselages and contains braces 126, 125 and 124 can be operated 40 by brace 126 or a like brace in the starboard 45 rather than the port fuselage. When the wings 1d and 1e are completely retracted and their trusses housed as indicated then the two smaller wings uniting with the internal tracks and internal wing trussing already described as associated with 1c will furnish the additional internal wing strength which was given previously to retraction by the three sets or sorts of bracing external trusses. The members 124 and 125 and kindred braces are understood to be housed as 50 are braces 97 in Figs. 28 and 29, and to lower the resistance of the said braces in flight when extended I provide collapsible streamlining 127, see Figs. 27, 28 and 29, consisting of a semiflexible cover or envelope 127 attached to the rear of the 55 said braces, since it is far more important to streamline the rear of a body to reduce wind resistance than it is the front thereof, and in Fig. 27, I show bent braces of stiff wire 128, journaled inside of said cover 127 and to the back of braces 60 like 97; Fig. 29 shows the streamlining collapsed as it will be when the braces are retracted and housed within the wing slots. One end of the streamlining can be attached to a portion of the wing slot so that, when the brace is extended it 65 pulls along the part designated 29, thus raising the wire wishbone shaped braces 128 into the positions shown in Fig. 27 and when these wires, which are attached to 127, are allowed to fall in the direction of the arrow 130 the entire streamlining will be in a position as shown in Fig. 29. As an alternative arrangement to the wire braces 128 I show in Fig. 28 an inflation valve 131 which will fill the streamline 127 with compressed air from an air bottle through the pipe 132 leading 70 75

from the pilot's cabin after the fashion disclosed in my Patent No. 1,728,621.

The radial air cooled motors 8 are a compact and mechanically efficient type of motor for aircraft, but interfere with the attainment of very high speeds as mounted and cooled in present practice, i. e., mounted within a cowling such as illustrated at 9 Figs. 1 and 17; such cowlings have a wide circular opening in front near the propeller and allow the heated air to escape at the end margins in front of the leading edge of the wing. In Figs. 12, 13 and 14, 49 and 50, I disclose a great improvement in cowls for radial cooled motors: Cowl 9a is supported at its rear margins by trussing 9b secured to the forward fuselage longerons just forward of the firewall 9c.

The motor 8 is also detachably secured to the said fuselage just forward of the said firewall and the crank case of the motor is internally and externally ribbed to assist it in taking the loads imposed by having to rigidly support the forward cantilever housing 9e, which incloses and supports the forward propeller shaft bearing 9d, located just aft of the propeller spinner 10a which has air louver exits in its nose.

A framework 9f supports the forward end of cowling 9a and between this frame and an intermediate frame 9g is rotatably mounted an inner sheet metal ring 9h capable of opening or closing the louvers 9i in the cowling 9a. Similar openings in the inner cowl 9h when brought into line with the outer openings 9i will admit air within the motor inclosure to cool the same and to cool the motor 8 after the fashion disclosed in my Patents Nos. 1,854,706 and 1,973,007 and 1,847,093.

This 9h may be rotated through a small arch by manual means (not shown), but in order to relieve the pilot of this regulating of the airflow about the cylinders of his motor I supply an automatic regulator in the form of a speed governor 10b of a well known sort which is driven from the propeller shaft 9d by bevel gears 10d; this governor or regulator 10b either pulls or releases a flexible cable 10e which leads around a pulley 10f to an attachment point on the said inner cowl 9h; a small spring 10g can be arranged between the frame 9g and the said inner cowl 9h to pull against the said cable 10e: Thus by adjusting the regulator 10b the number of revolutions made by the propeller shaft can be made to either open or close the air openings in the cowl 9a.

At 127 in Fig. 12 I have indicated a retractable chassis which can be constructed and operated as indicated by the aforementioned patents and pending applications: Its novelty lies mostly in its disposition on one side of each fuselage body, see Fig. 14, leaving room in the other side and in the region of the center of gravity so far as fore and aft balance is concerned for bombs 96.

128, Figs. 13 and 14, show remote control machine guns located in spaces which are not needed for the overlapping wings.

It is contemplated to blend the interior connections of my vision bulges with the interior walls 65 of the aircraft so as to provide smooth contacts for human beings.

As will be seen by viewing Figs. 1 through 11, inclusive, the action of my oceanplane in rough water will obviate the damage which would be caused by impinging green water represented by X in Figs. 9 and 11 although the whitecaps or foam represented by Z may cover portions or all of the bodies and wings. In a fore and aft direction the hull formation of my double boat bodies 2 will support the craft in the trough of a

heavy sea and by my device of removing the rear auxiliary Wragg wing from the region of the heavy water during the time the plane is riding out a severe gale, no damage will arise: However the long overhang of normal aspect ratio (6 to 1) of aeroplane wings overhanging their boat bodies in the trough of a heavy sea would bring the heavy water over the wing ends and crush the same if it were not for my device of either retracting the wings within the lateral ends of the main wing as shown in Figs. 1, 2, 3, 12, 13, 14, 17 and 19 or by means of the low aspect ratio wing type shown in Figs. 6, 7, 8 and 9 or by the still further alternative shown in Figs. 10 and 11. Thus in operation I have created a design which lacks the faults of current practice where either wing end floats which are too weak to stand heavy seas are used or stubby wings are used as floats near the bottom of a central hull. These are also too weak for the pounding of the sea and they have the additional disadvantage of ruining the airflow about the plane because of drag and interference. To reduce the drag and interference at the wing-body connections I have reduced the beam (see Figs. 5 and 6) of the hulls where they connect to the underside of the wing; but this weakens these connections so that they could not withstand the wrenching action of the waves without employing my retractable wing-body bracing at frames 6a and 6a. The subject matter dealing with the differential action of the Wragg type rear auxiliary wings when used as lateral controlling devices goes to Fig. 17 and its original with description in Serial No. 687,540 and it will be apparent that in the instant case I can use the two outermost Wrags as ailerons while using the central Wragg as a high lifting device or merely as a means of reducing the drag of the forward wing, which it does when in its full line position.

The loading and discharge of an oceanplane calls for invention to devise special means to facilitate ingress and egress of passengers and freight because the light structure of the large overhanging wings and tail surfaces cannot safely be brought into proximity to wharfs such as ships dock at for loading and discharging. The comparatively light and outspreading plane structure rolling about on the water surface, even of a land-locked harbor, calls for entirely different loading facilities than those associated with loading cranes or ship's derricks. It will be seen that I not only avoid the weight of the ship's loading booms by employing the wing extension, see right hand side of Fig. 6, to substitute for the usual "outboard" boom, but by providing a track with motorized tackle traveling close to the underside of the upper wing skin, I avoid need for the "mid-ship" boom which is used by vessels to lower the cargo down the hatches, furthermore the arrangement I show has a number of additional surprise features such as affording a vast expanse of overhead protection for cargo and passengers against rain or hail during the loading operations and, in an oceanplane with two hulls, such as shown (Figs. 6, 9 and 11) results in a steady influence to guide the elevator 37 so that it tends to center through the wing hatchways and deck hatchways. In case of partial flooding of one hull's compartments or shifting of ballast in flight my unique method of loading could be employed with ease to transfer heavy articles from one hull to another through the wing passage 11. Or if in flight a motor, such as 48 of Fig. 7, should need replacement my traveling

hoist could aid in that, and my disclosures in Figs. 4, 5 and 6 as well as 8 are so clear as to be unmistakable to those skilled in the art of aeroplane and of ship design. The traveling hoist 40 rolls athwartships through the passage 11 just forward of wing spar 5, where in Fig. 7 I have indicated a man 45 standing erect. The thickness of the wing at this passageway makes it easy to handle heavy, large articles without disturbing the oceanplane balance either on water or in the air, also the proximity of the fore wing spar 5 to the track 39a which is hung from the wing skin 24, see Fig. 6, affords good support with little extra weight.

15. Naturally the lower wing skin hatch 42 may be located electively either on the outboard side of the hulls or if a "lee" sheltered region is desired for the float 38 from waves and wind the hatch can be placed intermediate the hulls: In both cases the remote hull will steady the loading action against "listing" of the hull being loaded or discharged.

20. The utility of the retractable wing bracing such as shown in Figs. 12, 13, 14, and 19 to 29, inclusive, and 53 will soon become apparent as speeds rise above 350 M. P. H. and the need for overlapping wings for increasing fuel range is more completely understood and also the retracting braces will aid the strength of my oceanplane connections between hull and wing so that rough seas cannot wrench same apart: i. e. the braces will aid in making the oceanplane wave-worthy. It will be seen that I retain a slight overlapping strength within the wing see Fig. 14 before I retract the external wing braces.

25. The transparent material for the pilot's vision is carried in streamline form over and beyond the side of the body as at 70 (see Figs. 17 and 30) so the pilot without discomfort may see aft.

30. The transparent panel immediately abreast of the pilot's head slides over from port to starboard so that he may exit through that.

35. The special need for invention in respect to improved vision illustrated by my devices disclosed in Figs. 12, 13, 15, 16, 17, 18, 30, 31, 32, 33, 34, 35, 36, 37, 38 and 9 and 43 will be readily apparent to those acquainted with the very high and increasing velocities of modern aircraft and it will be apparent also that with only slight modification the various devices shown can be adapted for airship use or for the interior of a wing as well as for the walls of the oceanplane bodies. Whereas in my former disclosures the motor used to move a part such as, for example, a chassis strut

40. has been attached to a comparatively fixed part of the aeroplane, I now provide light individual drive motors, such as 101 which travel along with a part being moved. Also the streamlined form shown in Fig. 32 can be substituted for the round form shown in Fig. 37 as automatically operated; by that I mean that when one takes hold of the window opener to lower the plane glass window that a connecting mechanism, i. e., the cable 24, automatically and without special effort on the part of the operator brings into place the bulging form 78, see Figs. 34 to 38, inclusive. In like manner the bulging cockpit covers indicated in other views can be automatically raised or lowered or an electric motor of very small size such as is illustrated in Figs. 23 and 42 can be employed.

45. The disadvantage now suffered by planes using radial motors by reason of the drag creating type of flat front cowling can be dissipated by means of my invention shown in Figs. 12, 49 and 50 where I disclose a finely streamlined tapering type of

50. motor cowl which has an internal propeller shaft supporting extension from the motor crank case and which supports a means of varying the air-cooling apertures of the cowl in accordance with a governor to be regulated so that any desired revolutions of the said propeller shaft can become the automatic determining means for opening or closing the air cooling louvers of the cowl.

55. Wide variations may be made from the precise embodiments of my invention as in the drawings 10 and descriptions illustrated without departing from the teaching of the disclosures and I do not limit myself to the specific embodiments, but what I claim as new is:

1. A monoplane wing inclosing its principal trussing therewith in, two floatation hulls spaced apart laterally from the said wing's center and having wall hull sides braced by multiple built-up girder decks and frames and the said sides and frames uniting with the said wing trussing within the external skin thereof to withstand wave motion, auxiliary wings adjacent the rear portion of the said main wing and spaced apart downwardly and rearwardly therefrom by brackets and means available to an operator within the said monoplane, including power means, to strengthen the said union of hull sides and wing trussing to resist wave contacts in rough water.

2. The combination in a monoplane flying boat of a main wing and an auxiliary wing held by 30 brackets in a spaced apart position to rearward of the trailing edge of the said main wing, the said auxiliary wing journaled to turn through limited angles of attack about an axis located therewithin and means to alter the position of the said axis, to 35 bring the same over the trailing edge of the said wing, whereby the said auxiliary wing will be protected from wave impact by the rear portions of the said main wing.

3. In combination with a twin hull flying boat 40 type plane, a main wing having a front spar, multiple deck hulls subtended below the said wing, a thwartship frame of each said hull located below and structurally united with the said spar and a retractable brace extending from a point on the 45 lower surface of the said wing in the region of the said spar to a point on the side wall of each said hull in the region of the said frame and retractable bracing between the said hulls, whereby the wrenching action of the waves to separate 50 said wing and hull will be resisted by the said brace when the said boat-plane is on the ocean surface and the said brace may be retracted and housed during flight.

4. In combination with an oceanplane, a main 55 wing attached on the top portion of a floatation hull, and an auxiliary super-loading wing located to rearward and slightly below the said main wing and means operable from within the said oceanplane to move the said auxiliary wing to a position above the rear portion of the said main wing.

5. In a two-body type of flying machine, a main wing attached to and spacing the said two bodies apart, an auxiliary wing located to rearward of the said main wing and divided into three sections, the central of the said three sections located between the two said bodies and a combined supporting and operating means for the said sections passing through the side walls of the said bodies.

6. A combination according to claim 5 and the 70 said bodies being adapted to float on the water and means located within the said flying machine to move the said three sections simultaneously to a comparatively protected position in respect to wave contact.

7. A twin hull type flying boat having both said hulls attached to and subtended below a main wing, housings located in the under surface of the said wing, external bracing between the said hulls and wing and other braces between the said hulls and power means to retract the said bracing and house the same within the said housings.
8. In combination with a monoplane wing two spaced apart, multi-deck, ship hulls thereunder, multiple high lift devices extending laterally and rearwardly of the said wing and means including power means to withdraw all of the said devices into positions above portions of the said monoplane wing, where they will be protected from wave impact and whereby the flotation stability of the said hulls will be substantially increased.
9. In combination in an aeroplane having a main wing and wings telescopically extensible therefrom, housings provided in the under portion of the said wings, retractable wing bracing for the said telescopic wings, and means to retract and house the said bracing within said housings.
10. In combination with a main wing telescopic overlapping wings extensible therefrom and arranged to strengthen the said main wing when in completely retracted positions and external trussing movable into a position to strengthen the said main wing when the telescopic wings are extended.
11. In combination with a main wing having telescopic wings extensible therefrom, external bracing for the said wings, means for extending the said telescopic wings and co-incidentally extending the bracing therefor.
12. In a twin hull oceanplane having a wing extending across the twin hulls and secured to the upper portions thereof, said wing having a hatchway outboard of one of said hulls and a passageway within the wing extending from said hatchway over said one hull and a hatchway between said one hull and said passageway, the upper wall of the passageway being formed by the inner side of the upper skin of the wing: a trackway supported adjacent the upper wall of the said passageway and extending in said passageway from above the first hatchway to above the other hatchways, a traveling hoisting device mounted on said trackway for movement along the said trackway from above the first hatchway to above the other hatchways, whereby articles may be hoisted thru the first hatchway and lowered thru either of the other hatchways or transferred from one hull to the other or from either hull thru the first said hatchway.

JAMES V. MARTIN. 45
